By S. J. Van Stavoren
ATTORNEY.

UNITED STATES PATENT OFFICE.

GEORGE F. GODLEY, OF PHILADELPHIA, PENNSYLVANIA.

CAR-AXLE BOX.

SPECIFICATION forming part of Letters Patent No. 288,705, dated November 20, 1883.

Application filed September 19, 1883. (No model.)

To all whom it may concern:

Be it known that I, GEORGE F. GODLEY, a citizen of the United States, residing at Philadelphia, in the county of Philadelphia and State of Pennsylvania, have invented certain new and useful Improvements in Car-Axle Boxes, of which the following is a specification, reference being had therein to the accompanying drawings, wherein—

10 Figure 1 is a longitudinal vertical section of a car-axle box and my improvements, the latter being in section on the lines 1, 1, Fig. 2, which is a sectional elevation of the journal brass or bearing on the line 2, 2, Fig. 1. Fig. 15 3 is an elevation of the dust-shield, and Fig. 4 is a sectional elevation of a slight modification.

My invention has relation, principally, to devices placed within car-axle boxes for lubricating the journals and bearings of the axles, having especial reference to that class of axle-boxes wherein waste saturated with oil is used to effect the lubrication of the axle-journal and its bearing; and it has for its object to provide 25 a supply of oil which is kept free from dust, dirt, or grit, and is automatically conveyed or fed to the bearing and journal to continuously and properly lubricate said parts, whereby all danger of "hot boxes" due to the settling of 30 the saturated waste away from the journal is avoided.

My invention has for its further object to provide an inexpensive, simple, and durable dust-shield which not only excludes dust from 35 the axle-box, but also prevents leakage of oil from the latter.

My invention accordingly consists of the novel combination, construction, and arrangement of parts, as hereinafter more specifically 40 described and claimed, having reference particularly to the provision, first, of a brass or bearing having a depending closed or sealed oil box or reservoir and contained means for lifting or conveying the oil to the journal to be lubricated; second, of a brass or bearing having longitudinal slots filled with a packing of asbestos and black-lead or graphite, or other materials or compound possessing lubricating properties, in combination with means for lifting or conveying oil to the top of the journal

designed to be lubricated; third, of a car-axle box having a well for oil-saturated waste, and a brass or bearing having a depending closed or sealed oil-receptacle, and a spring, wick, or other suitable means for elevating oil from 55 said receptacle to the brass and its journal; and, fourth, of a dust-shield consisting of an annular coiled or spiral spring packed with wool, asbestos, felt, or other suitable material.

In the drawings, A represents a car-axle box 60 of the usual or other desired construction, having a well, a, for the reception of waste and oil a' for lubricating the axle B or its journal B' in the well-known manner. Said box has the customary vertical recess or chamber, a', 65 in its rear wall for a dust-shield, H.

C indicates the brass or bearing for the axle-journal B', having longitudinal undercut slots y, which may extend upwardly to near the top of the bearing, as illustrated in Fig. 2; or they 70 may pass entirely through it, if desired. In cross-section they may be parallel or of equal width, as shown at y, Fig. 2, or be made tapering or wedge-shaped, as indicated at x; or they may otherwise be arranged and configured as 75 desired. Said slots are filled with a packing, G, composed of asbestos, black-lead, soap-stone, or other ingredients possessing self-lubricating qualities may be used, as desired. Said packing also subserves the purpose of an 80 absorptive material for taking up the surplus oil fed to the axle-journal and holding it in reserve for lubricating purposes when the usual or other oil-supplies therefor have become exhausted.

At the forward end of the bearing C is attached a closed or sealed box or receptacle for holding a supply of oil; or said box and bearing may be formed integral with each other, as indicated, and have a central strengthening 90 rib or ribs, c'. Said box is provided with a filling-opening closed or sealed by a stopple, c', as shown in Fig. 1; or a hinged or other suitable removable lid may be substituted therefor, as indicated in Fig. 4.

The oil in box D is conveyed or raised to the journal B' by means of wicks or packing d, which pass into longitudinal channels c in bearing C, and thence into the communicating and enlarged vertical channels c', as shown in Fig. 100

1, so that the upper ends of said wicks contact with the journal B', which wipes or brushes off the oil therefrom.

The channels *c c'* may be located one on each 5 side of the rib *e'*, as shown, or otherwise suitably disposed as desired.

The wicks *d* may be of cotton, wool, felt, or other fibrous or absorptive material; or a coiled spiral spring or zigzag bent wire with 10 or without a fibrous packing may be used, in which case the vibration of the spring or bent wire due to the jolting of the axle-box will assist the capillary action of the wicking to more effectually feed the oil to the bearing C.

15 The last-named construction of wick is shown in Fig. 4; but, if desired, any other suitable means may be employed to convey oil from box D to bearing C. Said box may be provided with a central aperture, *e*, into which 20 is inserted a steel or hard-metal pin, *F*, with head *f* standing in front of journal B', as shown, for the end of the axle to abut against and prevent its longitudinal movement mutilating or straining the box D.

25 When the bearing C and box D are constructed and arranged as shown in Fig. 1, the axle may be collarless; but when said parts are to be used upon an axle having a collar, a transverse slot is formed on the under side of 30 the bearing adjacent to said collar for it to work or revolve in. Such construction is represented in Fig. 4.

The operation is obvious. When the oil-box D is used in connection with the waste and 35 oil in well *a*, the journal B' is supplied with oil both above and below it, or has two sources of supply, and is thereby thoroughly lubricated. Surplus oil fed thereto is taken up by the packing G, so that in case the oil in box 40 D becomes exhausted and the waste *a'* settles or falls away from journal B', said packing supplies the necessary lubricant for preventing heating of said journal, or avoiding what is technically called a "hot box."

45 If desired, the packing G and slots *g* may be dispensed with, in which case the supply of oil in box D is depended upon to prevent the heating of the journal when the waste *a'* settles away therefrom. So, too, the bearing 50 C and box D may alone be used for lubricating the journal B'; and, if desired, said box D may then extend backward under said journal, to afford an increased oil-supply therefor.

The shield H is composed of an annular 55 coiled spring of varying width or diameters in cross-sections, as shown, the coils on its upper and lower parts being larger than those on or composing its sides, so that as the bearing C wears and the axle rises in the box A, said 60 shield still closes and seals the opening in the rear wall of the axle-box; but, if desired, the coils of spring H may all be of the same diameter, and may be oblong in cross-section, as shown, or otherwise suitably configured. 65 To insure close contact between said spring, axle, and walls of box A, the spring is packed

with wool, felt, asbestos, or other fibrous or absorptive material, (represented at *h*.) which not only serves to exclude dust and dirt from the well *a*, but also prevents leakage of oil 70 from the box A.

I have shown the oil-box D secured to or formed on the forward end of the bearing C; but I do not confine myself thereto, as said box may depend from and extend along either or 75 both longitudinal sides of the bearing, in which case the axle-box may be made wider than is now customary, to accommodate such construction of bearing and depending oil-boxes. So, too, while I have shown my improvements applied to an axle-box having a well for waste and oil, it is obvious that said waste may be dispensed with, and the oil in box D be alone relied upon for effecting a lubrication of the axle-journal and its bearing. 80 Again, I do not confine myself to the use of the wicks *d* for conveying the oil from box D to bearing C, as a tube having a small bore, through which the oil will pass by capillary attraction, or a pump operated by the vibratory action of the car or axle-box, may be substituted therefor; or any other suitable or desired means may be used to effect such result.

I am aware that brasses or bearings for 95 journals have been recessed or made hollow, for the purpose of holding a supply of oil which is conveyed to the bearing-surfaces by wicks; but my invention does not embrace such construction, as the oil-box is independent of the brass, although formed integral therewith.

What I claim is—

1. A brass or bearing for journals, provided with a depending closed or sealed oil-box, and 105 means for conveying oil to the bearing-surface of the brass, substantially as shown and described.

2. The brass or bearing C, having slots formed therein which are filled with a self-lubricating or absorptive packing, and a depending oil-box with means for raising or conveying the oil to the bearing, substantially as 110 shown and described.

3. The brass or bearing C, having slots *c c'*, oil-box D, with filling-opening having a removable cover, and means for conveying oil from said box to and through said channels, substantially as shown and described.

4. The brass or bearing C, having depending oil-box D, carrying an abutting pin or block, and means for conveying oil to the bearing, substantially as shown and described.

5. The brass or bearing C, having oil-box D, with central opening, *e*, pin or block *F*, and wicks *d*, substantially as shown and described.

6. In combination with a car-axle box, the bearing C, having packing G and box D, and means for conveying oil from box D to said bearing, substantially as shown and described.

7. In combination with a car-axle box, the bearing C, having depending closed or sealed

- oil-box D, and means for conveying oil from the latter to said bearing, substantially as shown and described.
8. In combination with car-axle box A, having well a, packed with waste saturated with oil, a brass or bearing, C, having oil-box D, and means for conveying oil from the latter to said bearing, substantially as shown and described.
9. A dust-shield for car-axle boxes, composed of an annular coiled spring packed with a fibrous or absorptive material, as and for the purpose set forth.
10. The dust-shield H, composed of an annular coiled spring of varying widths in different cross-sections, and packed with a fibrous or absorptive material, substantially as shown and described.
11. In combination with a car-axle box, the brass or bearing C, having channels c c', oil-box D, and coiled spring or zigzag bent rod, wick, or conveyer, with or without a fibrous or absorptive packing, substantially as shown and described.
12. A brass or bearing having depending oil-box secured to or formed thereon, and means, substantially as shown and described, for conveying oil from the box to the bearing, as set forth.

In testimony whereof I affix my signature in presence of two witnesses.

GEORGE F. GODLEY.
